UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed August 5, 1921. Serial No. 490,083.

This invention comprehends improvements of general utility in the coking retort oven art, and also comprehends certain improvements especially applicable to coking retort ovens of the well known cross-regenerative type exemplified in the patents to H. Koppers, No. 818,033 and No. 1,026,169.

The invention has for objects the provision of a coking retort oven having, as important characteristics: a system of regenerative operation which permits employment of the combination oven principle, exemplified in the Koppers Patent No. 1,026,169, above referred to, without any necessity for varying the size of the duct connections between the regenerators and the flame flues in converting such a coking retort oven from operation as a "gas oven", i. e., with the employment of an extraneously derived gas, such as producer gas for fuel, to operation as a "coke oven" employing coke oven gas as the fuel. Coke oven gas and producer gas are widely different in their characteristics. Coke oven gas is a relatively rich gas requiring for proper combustion a relatively large volume of air supplied at a relatively high velocity, in order to avoid flame concentration in the lower regions of the flame flues. On the other hand, producer gas being much poorer in quality, requires for proper combustion a relatively smaller air volume supplied at a relatively reduced velocity. In combination ovens, the regenerators which are employed for supplying preheated producer gas to the flame flues during producer gas operation are, when the oven is converted to coke oven gas operation, employed for delivering air to the flues as well as the other regenerators which supply air, whether the battery be operating with producer gas or with coke oven gas. That is to say, during coke oven gas operation all of the regenerators supply air to the flues during the in-flow period, whereas, during the producer gas operation, some of the regenerators supply air and others supply producer gas. The regenerative area of the battery employed for air is thus approximately doubled, with respect to the inflow, whenever a combination oven battery is converted from producer gas operation to

coke oven gas operation. Inasmuch as the duct connections between the regenerators and the flues must be made large enough to handle the relatively large volume of producer gas, which flows into the flame flues at a relatively reduced velocity, it follows that when these regenerators are employed for delivering air, during coke oven gas operation, the duct connections will deliver the air in the requisite volume but with a reduced velocity that would tend to promote flame concentration in the lower region of the flame flues. Consequently, it has been customary, in converting the combination oven from producer gas to coke oven gas operation, to restrict the duct connections between the regenerators and the flues by partially plugging them in order to promote the requisite velocity in flow of the air. This plugging operation, however, in the coke oven battery of commercial magnitude is a tedious and lengthy one, and it is the purpose of this invention to supply to the flues of a combination oven, during coke oven gas operation, air in the requisite volume and velocity, by the novel expedient of restricting the regenerative area that operates at any one time for in-flow of air and causing the entire volume of air required for combustion in the flame flues to pass through this restricted regenerative area and thus to increase the velocity of the air flow to a degree which avoids flame concentration. This is accomplished by causing the air to travel through only a part of the regenerative area operating for in-flow, at any one time, while the remainder of the in-flow operating regenerative area remains for the time being substantially inoperative as regards the flow of gaseous media to the flues and then effecting a reversal, during the same in-flow period, which renders inoperative that part of the regenerative area which previously supplied the air and utilizes the previously inoperative part of the regenerative area for the air supply to the flues.

In addition to the general objects recited above, the invention has for further objects such other improvements or advantages in construction and operation as are found to

obtain in the structures and devices herein-after described or claimed.

In the accompanying drawings forming part of the specification and showing, for purposes of exemplification, a preferred form and manner in which the invention may be embodied and practiced, but without limiting the claimed invention to such illustrative instance or instances:

Figure 1 is a composite crosswise vertical section through a coke oven battery embodying the combination oven principle of the aforesaid prior patent to H. Koppers, No. 1,026,169 and equipped with the improvements of the present invention, the view being taken longitudinally through a coking chamber and a pair of regenerators;

Fig. 2 is a vertical sectional elevation taken longitudinally of the coke oven battery:

Fig. 3 is a vertical sectional elevation taken transversely of the coke oven battery through a portion of one of the heating walls and illustrating the gas flow through the flues of the heating walls;

Figs. 4 and 5 are diagrammatic views of the regenerators and connected parts illustrating the mode of operation of the improved reversal system of the present invention;

Fig. 6 is a horizontal section through the regenerators of the coke oven battery showing in plan the various connections and devices for reversing the flow through the regenerators and through the flues;

Fig. 7 is a vertical section taken longitudinally of the battery through the air boxes and waste gas tunnel or stack flue and showing the reversing connections on one side of the battery; and

Fig. 8 is a view similar to Fig. 7 but showing the reversing connections on the other side of the battery.

The same characters of reference designate the same parts in each of the several views of the drawings.

In the embodiment illustrated in the drawings, the invention is incorporated in a combination coke oven battery, i. e.,—a battery having provision for being operated either with producer gas as the fuel, or with the coke oven gas derived from the distillation of the coal in the coking chambers or retorts of the battery. For convenience, the present description will be confined to the present illustrative embodiment of the invention in such a combination coke oven battery; the novel features and improvements made by the invention are susceptible of other applications, such for example, as other heating furnaces embodying the regenerative principle; hence, the scope of the invention is not confined to the specific use and specific embodiment herein described as an illustrative example.

Referring to the drawings, there are illustrated views of a coke oven battery or plant

of the by-product type, having features above specified; said oven battery embodies in its construction a plurality of crosswise elongated heating walls 11, 11, and a plurality of intermediate crosswise elongated coking chambers 12, 12. The heating walls 11 form the side walls of the respective coking chambers 12, as shown more particularly in Fig. 2, and, in the present instance, are directly supported by the heavy supporting or pillar walls 13, 13, which extend crosswise of the battery and are located beneath the respective heating walls 11, 11. These pillar walls collectively form the main support for the entire superstructure of the oven battery, and are themselves supported upon a flat mat or platform which constitutes the sub-foundation on which the entire battery rests. The coal to be coked is charged into the several coking chambers or ovens through charging holes 14 located in the top 15 of the oven battery and positioned directly above the ovens or chambers 12, as shown in Fig. 1. These charging holes 14 are equipped with the usual removable covers, which are removed during charging of the individual ovens or coking chambers and are placed in position to close the tops of such ovens during the entire coking or distilling operation. The gases of distillation pass from the tops of the several coking chambers 12 through gas outlets 16 and thence through ascension pipes (not fully shown) into the usual gas collecting main which carries the distillation products to the by-product apparatus.

Heat for coking the charges of coal in the several ovens or chambers 12 is derived from the heating walls 11 which, as above mentioned, extend crosswise of the battery at the sides of the coking chambers. Referring now more particularly to Figs. 2 and 3, each heating wall 11 is constituted of a plurality of flame or combustion flues 17. The flame flues of each heating wall are, in accordance with the present adaptation of the invention, operatively disposed into two groups. When the flame flues of one group on one side of the battery are burning, that is to say, operating for up-flow, the flame flues on the opposite side of the battery are operating for down-flow to prevent waste of the gases. All the flame flues on one side of the battery operate concurrently for flow in the same direction, while all the flame flues of the other group on the other side of the battery are operating concurrently for flow in the opposite direction.

The crosswise regenerators 18 of the retort oven are located at a lower level than the aforesaid coking chambers and, in the present instance, extend in parallelism between the pillar walls 13 and partition walls 13¹. Located in the middle lengthwise vertical plane of the battery is a vertical partition 19, as shown in Fig. 1, which parti-

tion extends all the way up from the mat of the battery to the bottom of the overlying coking chamber and from one to the other of the pillar walls 13. The regenerators, which 5 are respectively located on the opposite sides of the battery, extend inwardly to said partition 19 and are separated thereby, as clearly shown in Fig. 1, the partition 19 serving to separate the in-flow operating regenerators 10 on one side of the battery from the out-flow operating regenerators on the other. Each regenerator 18 is a chamber containing open brick work, commonly called checkerwork, and indicated at 20, with distributing sole 15 channels 21 underneath such checkerwork, the channels forming the soles of such chambers and opening up into the checkerwork.

The regenerators are heated, in alternation, by the hot combustion products that draw 20 off from the flame or combustion flues hereinbefore mentioned and then impart such heat into the media that they feed into these flues. As shown, the several regenerators of the battery are operatively disposed into two series 25 K and L respectively located on opposite sides of the battery. Each such series of regenerators is furthermore operatively disposed into two groups M and N, the regenerators of the group M alternating with the regenerators of the group N. Each regenerator, whether of the group M or N, is provided with a series of ducts 23, leading respectively to individual flame flues 17 of the two heating walls adjacent to such regenerator, it being understood that each duct 23 is provided, as usually, with the usual gas controlling means, such as the customary sliding bricks 23¹, for restricting the ducts 23 for regulation of gas flow therethrough. 30 Inasmuch as the regenerators of the group M alternate with those of the group N, each flame flue 17 of each heating wall communicates by a pair of ducts 23 with adjacent regenerators, one of the group M and the other 35 of the group N.

All of the flues on one side of the central partition 19, as well as their communicably connected regenerators, are operating for in-flow, while concurrently all of the flues on the other side of the battery and their communicably connected regenerators are operating 40 concurrently for out-flow. The reversal in flow through the flame flues and their communicably connected regenerators may thus be said to take place transversely of the battery, in accordance with a common practice in this art.

Each flame flue 17 has at its top a port or opening 24 for draft and the passage of combustion products from the flame in the flue. These ports 24 open up into horizontal or bus flues 25 formed in the heating walls and connecting the flame flues of the in-flow operating groups with the flame flues of the down-flow operating groups. The draft

through the ports 24 may be regulated by means of the usual dampers or sliding bricks 27, positioned in the ordinary way in the bottoms of the horizontal flues 25 and adapted to be reached by access flues 28 which extend 50 from the top of the horizontal flues in each heating wall to the top 15 of the battery, there being an access flue positioned over each flame flue of each heating wall.

Extending crosswise of the battery in each pillar 13 and located below the heating wall 11 thereabove is a pair of gas supply channels 29 and 30. These channels 29 and 30 are for the purpose of supplying coke oven gas to the several flame flues on each side of the central line T, and to accomplish this end, the channel 30 communicates with the individual flues 17 on one side of said line T by means of ducts 31 that lead from said channel 30 inwardly into the bottoms of individual flues; and the channel 29 which supplies the several flues that are located on the other side of the before-mentioned line T communicates therewith by means of similarly connected ducts. Within the several ducts are disposed the usual nozzles 32. The supply of coke oven gas to the respective channels 29 and 30 is derived from coke oven gas mains of the usual type and respectively located on opposite sides of the battery and extending longitudinally therealong. Suitable means is provided for admitting or cutting off the supply of gas with respect to the channels 29 or 30, it being understood that the gas supply is concurrently maintained in all of the channels of one series 29 or 30. For operating the battery alternatively with the use of a special generator gas, such as producer gas, the regenerators of the groups M, when operating 55 for in-flow, may be optionally connected with a producer gas main, by mechanism such as is disclosed in my application for patent for a coking retort oven, filed April 23, 1920, Serial No. 376,126, now Patent No. 1,416,322, so that the producer gas may be directed into such 60 of the regenerators 18 as are operating for in-flow and conveyed through these regenerators into burning flame flues 17.

Referring now more particularly to Figs. 6, 7, and 8, the sole channels 21 of the groups of regenerators M of both series K and L, respectively communicate with flow-boxes 33; similarly the sole channels of the regenerators of the several groups N on both sides of the battery respectively communicating with flow-boxes 34. This results in the arrangement of two series of flow-boxes 33 and 34 along both sides of the battery, the flow-boxes of each series being disposed into pairs, which pairs alternate with the pairs of flow-boxes of the other series.

The several flow-boxes of the series 33 are provided with lids 35 for opening and closing the interior of such flow-boxes to the outer air, and the several flow-boxes of the series 34

are respectively provided with similar lids 36. Each air box lid 35 is provided with a lid-operating lever 37, and each air box lid 36 is provided with a similar lid-operating lever 38. Two waste gas tunnels or stack flues 51 and 52 extend longitudinally of the battery, one on one side of the battery and the other on the other side, said stack flues lead to the usual stack and adapted to be alternately placed in communication with or shut off from the stack by means of the usual main stack damper. That is to say when the stack flue 51 is in communication with the stack, the stack flue 52 is cut off from such communication, or vice versa. Each flow-box 33 or 34 on one side of the battery is adapted to be communicably connected with the stack flue 51 through a channel 57; similarly each flow-box 33 or 34 on the opposite side of the battery is adapted to be communicably connected through a channel 59 to the waste gas tunnel 52. As out-flow is maintained only in the regenerators on one side of the battery, the waste gas tunnels 51 and 52 operate alternatively to convey waste gas from the battery to the stack.

The several flow-boxes of the groups 33 on both sides of the battery are each provided with mushroom valves 60 for opening and closing their respective boxes relatively to the waste gas tunnels 51 and 52, the mushroom valves 60 being open when the regenerators, communicating with such flow-boxes on one side of the battery, are operating for out-flow, and the mushroom valves being closed when such regenerators are operating for in-flow. The purpose of these mushroom valves is to shut off the flow-boxes to the groups M of regenerators directly from the stack flues, when such regenerators are operating for in-flow, in order to prevent leakage of producer gas into the stack flues, during producer gas operation. The mushroom valves 60 are operated by valve-operating levers 62. All of the valve-operating levers of the series 62 are controlled and operated by a single cable 3 which leads to the damper reversing machine 65. On one operation of said machine 65, all the mushroom valves of the flow-boxes 33 on one side of the battery are opened to establish communication between such flow-boxes and a waste gas tunnel, while concurrently the mushroom valves of the flow-boxes on the other side of the battery are closed to cut off such flow-boxes from communication with the other waste gas tunnel; on reverse operation of the machine 65, the previously opened mushroom valves are closed and the previously closed mushroom valves are opened.

According to the invention, the lid-operating levers 37 of the groups 33 and the lid-operating levers 38 of the groups 34 on one side of the battery are controlled and operated by the reversing cable 2 leading to the air valve

reversing machine 66. Similarly the lid-operating levers 37 and 38 of both groups of flow-boxes on the other side of the battery are controlled and operated by the reversing cable 1 leading to the air valve reversing machine 67. As shown, a single operation of each reversing cable 1 or 2 is effective to open only the air box lids of one group of regenerators M or N corresponding to such reversing cable. Consequently the operation of placing the several regenerators of the groups M and N on one side of the battery in communication with a waste gas tunnel 51 or 52 by opening up the stack valve of that tunnel, and the mushroom valves 60, corresponding to the flow-boxes 33 of such regenerators, will be accompanied by an operation of the reversing cable on the other side of the battery that is effective at this time to open the air box lids 35 of only the regenerators of the groups M that have been switched to the in-flow operation.

A reverse operation of the cable 2 is necessary to open the air box lids of the groups N, but such reverse operation is accompanied by a closing of the previously opened air box lids of the groups M.

With the above described construction, it is thus possible, during coke oven gas operation, to require all of the air to flow through alternate regenerators of the in-flow operating regenerators on one side of the battery, while all of the out-flow regenerators on the other side of the battery are in communication with the exhaust. The principle of operation of the invention is illustrated in Figs. 4 and 5, which show diagrammatically the reversal system during a complete cycle of operation comprising two complete half-hour reversal periods. At the beginning of a reversal period, all of the regenerators M and N on one side of the battery are placed in communication with the exhaust and operate concurrently as waste gas regenerators W, for the first fifteen minutes of the complete half-hour reversal period, referring to the left hand side of Fig. 4, the alternate regenerators comprising the group M are placed in communication with the air for supplying air to the in-flow operating flues and thus operate as air regenerators A, while the other regenerators comprising the group N remain inoperative with respect to flow into the flues, such regenerators being designated by the reference character D. At the end of the fifteen minute interval, the reversing machine 66 is operated to reverse the cable 2 so that the regenerators D, comprising the group N of the in-flow operating regenerators are placed in communication with the air and become air regenerators A, whereas the regenerators A comprising the groups M are cut off from the air and become inactive with respect to the flow through the flues. At the end of the complete thirty minute op-

- erating period, all of the regenerators of the groups M and N that previously operated alternatively for in-flow are placed in communication with the exhaust, becoming waste 5 gas regenerators W, and the regenerators of the group M on the opposite side of the battery, are by one operation of the reversing machine 67 placed in communication with the outer air, while the regenerators of the group 10 N remain inoperative. When this reversal period is substantially half completed, the reversing machine 67 is reversely operated to permit air to flow into the regenerators of the group N so that they become air regenerators 15 A, and to cut off the air from the regenerators of the group M so that they become non-functioning regenerators D.
- The invention, as hereinabove set forth, is embodied in a particular form of construction, but may be variously embodied within the scope of the claims hereinafter made.
- I claim:
1. In a coking retort battery, in combination: a series of alternate coking chambers and heating walls therefor arranged side-by-side in a row, each of said heating walls comprising vertical combustion flues; rich gas supply means for supplying unpreheated fuel gas to said flues for combustion therein; crosswise regenerators disposed in two series; one series on each side of the battery, the regenerators of each series being communicably connected in pairs with the flues of said heating walls by regenerator ducts leading into the individual flues at their lower parts; and the regenerators of each pair when operable for inflow being jointly operable for conveying air to said flues during operation for combustion of said rich gas in said flues or alternatively separately operable to convey air and unpreheated leaner fuel gas separately and simultaneously to said flues for optional heating of the oven by combustion of preheated leaner fuel gas in said flues; gas control means for restricting the afore-said regenerator ducts; waste gas exhaust means for exhausting waste gas from said regenerators; air supply means for supplying air to said regenerators; and mechanism, adapted to operate during optional heating of the battery by combustion of unpreheated richer fuel gas in said flues, for establishing communication between one of said series of said regenerators and said waste gas exhaust means, while concurrently opening the air supply means for one regenerator of each pair of regenerators in the other series of regenerators and thereafter closing said air supply means for said regenerators and opening the air supply means for the other regenerator of each pair thereof in said other series of regenerators.
  2. In a coking retort battery, in combination: a series of alternate coking chambers and heating walls therefor arranged side-by-side in a row, each of said heating walls comprising combustion flues; rich gas supply means for supplying unpreheated rich fuel gas to said flues for combustion therein; regenerators operatively disposed in two sets operable in alternation with each other for inflow of combustion media and outflow of waste gas; the regenerators of each set being communicably connected in groups with the flues of said heating walls by regenerator ducts and the regenerators of each group when operable for inflow being jointly operable for conveying air to said flues during operation for combustion of said rich gas in said flues or alternatively separately operable to convey air and preheated leaner gas separately and simultaneously to said flues for optional heating of the battery by combustion of unpreheated leaner fuel gas in said flues; gas control means for restricting the afore-said regenerator ducts; air supply means for supplying air to said regenerators; waste gas exhaust means for exhausting waste gas from said regenerators; and mech-

anism, adapted to operate during optional heating of the battery by combustion of unpreheated fuel gas in said flues, for establishing communication between one of said sets of regenerators and said waste gas exhaust means, while concurrently opening the air supply means for part of the regenerators of each group of regenerators in the other set of regenerators and thereafter opening the air supply means for another part of the regenerators of each group of regenerators in the said other set of regenerators.

In testimony whereof I have hereunto set my hand this 30th day of July, 1921.
